UNITED STATES PATENT OFFICE

EARL H. ODELL, OF CHICAGO, ILLINOIS

VACUUM-CUP ENERGIZER

Application filed June 27, 1927. Serial No. 201,570.

This invention relates to a vacuum cup energizer on which the person lies when exercising which energizer is useful in exercising the body and in stimulating circulation of the blood.

5 It is an object of this invention to provide an exercise apparatus adapted to invigorate the body by causing a flow of blood to the surface of the body, thus inducing rapid circulation through the veins.

10 Other and further important objects of this invention will become apparent from the disclosure in the following specification and appended claims.

15 In the accompanying drawing which illustrates a preferred embodiment of this invention and in which similar reference numerals refer to similar features in the different views:

20 Figure 1 is a top plan view of the device, showing its application;

Figure 2 is an enlarged top plan view of the device;

25 Figure 3 is a sectional view taken on line III—III of Figure 2, and

Figure 4 is an end elevational view of the device.

As shown on the drawing:

The reference numeral 1 indicates a vacuum cup exercise apparatus embodying the principles of my invention and comprising a board 2 having extending from the front face thereof a plurality of vacuum cups 3. Said vacuum cups 3 are formed of resilient material, 30 such as rubber, with a cuplike portion 4 terminating in a circular rim 5 and a rearwardly extended portion 6. Said extended portion 6 is inserted through apertures 7 formed in the board 2 and held in place therein by 35 a flange 8 adapted to engage the rear face of the board 2. Said extended portion 6 is preferably formed with a hollow recess 9 so that the same may be squeezed through the aperture 7.

40 The vacuum cups 3 are preferably arranged

with the rims 5 of adjacent cups slightly spaced from each other. Said rims 5 thus lie in the same plane and present a substantial area for contact with the body.

As illustrated in Figure 1, a person 10 exercising on the device lies upon the vacuum cups 3 and by suitable body movements compresses the cups 3 in contact with the body to cause them to exert a pull upon the body. The partial vacuum thus created within the 50 cups 3 causes the blood to rush to the portions of the body surface engaged by said cups with the result that a rapid circulation of the blood is produced. In order to exercise the body muscles, the body should be twisted into and out of contact with the vacuum cups 3 so that the vacuum cups may exert a pull upon the body muscles. In this way a very invigorating action results and at the same time the body muscles are strengthened and rendered 55 more supple. If desired, a person need only lie pensively upon the device, in which case the cups 3 will act effectively to produce the desired circulation. The device may be used as a mat or as a table top, depending upon 60 what treatments are administered to a patient.

70 I am aware that many changes may be made and numerous details of construction may be varied through a wide range without departing from the principles of this invention, and I, therefore, do not purpose limiting the patent granted hereon, otherwise than necessitated by the prior art.

75 I claim as my invention:

1. An energizing device, comprising a 80 board having apertures therein and a plurality of rubber vacuum cups having rearwardly extending hollow flanged portions adapted to extend through said apertures with said flanges engaging the rear side of said board, 85 the rims of said vacuum cups lying in the same plane and presenting a surface for supporting a person's body.

2. An exercising device comprising a rigid 90 base, and a plurality of vacuum cups remov-

ably supported thereon and arranged closely together to provide a support for a person's body.

3. An exercising device in combination a rigid base, and a plurality of vacuum cups supported thereon and arranged closely together to provide a support for a person's body.

In testimony whereof I have hereunto subscribed my name at Chicago, Cook County, Illinois.

EARL H. ODELL.
